UNITED STATES PATENT OFFICE.

ALFRED L. BUCKLAND, OF MARIETTA, MINNESOTA.

SUGAR-DISPENSER.

1,270,262.

Specification of Letters Patent. Patented June 25, 1918.

Application filed February 18, 1918. Serial No. 217,893.

To all whom it may concern:

Be it known that I, ALFRED L. BUCKLAND, a citizen of the United States, residing at Marietta, in the county of Lac qui Parle 5 and State of Minnesota, have invented a new and useful Sugar-Dispenser, of which the following is a specification.

This invention relates to a sugar dispensing device, one of its objects being to provide 10 a simple structure which can be used for dispensing a measured quantity of sugar and the like, it being possible readily to adjust the device to vary the quantity dispensed thereby.

15 A further object is to provide a structure of this character which can be filled readily without disturbing the parts and which can be easily kept clean.

With the foregoing and other objects in 20 view which will appear as the description proceeds, the invention resides in the combination and arrangement of parts and in the details of construction hereinafter described and claimed, it being understood 25 that changes in the precise embodiment of the invention herein disclosed can be made within the scope of what is claimed, without departing from the spirit of the invention.

In the accompanying drawings the preferred form of the invention has been 30 shown.

In said drawings:—

Figure 1 is a central vertical section through the device; and

35 Fig. 2 is a section on line 2—2 of Fig. 1.

Referring to the figures by characters of reference 1 designates the body of the container the same being provided preferably with the threaded neck portion 2 adapted 40 to be engaged by a cap 3. This cap has a filling opening 4 from which extends a threaded neck 5 for the reception of screw plug 6.

The bottom of the body 1 is inclined 45 downwardly toward a depression 7 located at the center thereof and which is preferably cylindrical as shown, the said bottom being indicated at 8.

Secured to and projecting downwardly from the cap 3 is a measuring and dispensing tube 9 the lower end of which is adapted to fit snugly within the recess 7 and is provided with an elongated opening 10 close to the bottom 8. A sleeve 11 is adjustably mounted on this tube 9 and can be adjusted 50 longitudinally so as to partly or entirely cover the opening 10.

The tube 9 projects outwardly beyond the cap 3 and has its free end normally closed by a hinged flap 12 which is preferably 60 provided with a weight 13 whereby it is held normally closed.

In using the device the sleeve 11 is adjusted along the tube 9 so as to partly cover the opening 10, if so desired, so that the 65 distance between the lower end of the tube and the bottom of the sleeve will be such as to permit a certain quantity of sugar or the like to gravitate through the opening 10 and into the tube. When the sleeve is in one position the tube can be caused to contain a 70 teaspoonful of the material and, when the sleeve is in another position, a tablespoonful may enter the tube through the opening 10.

The body 1 is filled by pouring the material through the opening 4 and will be supported around the tube 9, a portion of the material gravitating through the opening 10 and into the lower end of the tube 9. By inverting the container that portion of 80 the material within the tube will gravitate downwardly through the tube and into a receptacle provided therefor, it being understood that the flap 9 will open automatically 85 during this operation. As soon as the device is placed upon its base or in its normal position, the lower portion of the tube 9 will refill and the device will again be ready for use.

What is claimed is:—

90 A dispensing device including a body having a depression in the center of the bottom thereof, a cap detachably engaging the body and having a filling opening, a tube extending through and removable with the cap, 95 one end portion of the tube being fitted

snugly and removably within the depression, there being an aperture in the tube and close to the depression, a sleeve slideable on the apertured portion of the tube and
5 movable against the bottom of the body to seal the lower end of the tube, and a weighted closure upon the outer end of the tube.

In testimony that I claim the foregoing as my own, I have hereto affixed my signature in the presence of two witnesses.

ALFRED L. BUCKLAND.
